(57) **CLAIM**

The ornamental design for a beverage cap with filter, as
shown and described.

DESCRIPTION

FIG. 1 is a top front perspective view of our new design for
a beverage cap with filter;

FIG. 2 is a top rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a bottom front perspective view thereof;

FIG. 10 is a bottom rear perspective view thereof;

FIG. 11 is a top front perspective view of our new design
with filter removed for clarity of disclosure;

FIG. 12 is a top rear perspective view thereof;

FIG. 13 is a front elevation view thereof;

FIG. 14 is a rear elevation view thereof;

FIG. 15 is a left elevation view thereof;

FIG. 16 is a right elevation view thereof;

FIG. 17 is a top plan view thereof;

FIG. 18 is a bottom plan view thereof;

FIG. 19 is a bottom front perspective view thereof;

FIG. 20 is a bottom rear perspective view thereof;

FIG. 21 is a top perspective view of our design with cap
removed for clarity of disclosure;

FIG. 22 is a front elevation view thereof;

FIG. 23 is a rear elevation view thereof;

FIG. 24 is a left elevation view thereof;

FIG. 25 is a right elevation view thereof;

FIG. 26 is a top plan view thereof;

FIG. 27 is a bottom plan view thereof;

FIG. 28 is a bottom front perspective view thereof;

FIG. 29 is a top front perspective view of a cap portion of
our new design, shown separately for clarity of disclosure;

FIG. 30 is a top rear perspective view thereof;

(Continued)

FIG. 31 is a front elevation view thereof;
 FIG. 32 is a rear elevation view thereof;
 FIG. 33 is a left elevation view thereof;
 FIG. 34 is a right elevation view thereof;
 FIG. 35 is a top plan view thereof;
 FIG. 36 is a bottom plan view thereof;
 FIG. 37 is a bottom front perspective view thereof;
 FIG. 38 is a bottom rear perspective view thereof;
 FIG. 39 is a top perspective view of a connection component of our new design, shown separately for clarity of disclosure;
 FIG. 40 is a front elevation view thereof;
 FIG. 41 is a rear elevation view thereof;
 FIG. 42 is a left elevation view thereof;
 FIG. 43 is a right elevation view thereof;
 FIG. 44 is a top plan view thereof;
 FIG. 45 is a bottom plan view thereof;
 FIG. 46 is a bottom perspective view thereof;
 FIG. 47 is a top perspective view of a filter portion of our new design, shown separately for clarity of disclosure;
 FIG. 48 is a front elevation view thereof;
 FIG. 49 is a rear elevation view thereof;
 FIG. 50 is a left elevation view thereof;
 FIG. 51 is a right elevation view thereof;
 FIG. 52 is a top plan view thereof; and,
 FIG. 53 is a bottom plan view thereof.
 The broken lines in the drawings depict portions of the beverage cap with filter that form no part of the claimed design.
